(57) **CLAIM**

The ornamental design for a basketball, as shown and described.

DESCRIPTION

FIG. 1 is an isometric view of a basketball according to a first embodiment of the present invention;

FIG. 2 is a front view thereof with the rear view being identical;

FIG. 3 is a left side view thereof with the right side view being identical;

FIG. 4 is a top view thereof;

FIG. 5 is a bottom view thereof;

FIG. 6 is an isometric view of a basketball according to a second embodiment of the present invention;

FIG. 7 is a front view thereof with the rear view being identical;

FIG. 8 is a left side view thereof with the right side view being identical;

FIG. 9 is a top view thereof; and,

FIG. 10 is a bottom view thereof.

The stippling is used in the drawings to show contrast in appearance between the stippled and unstippled areas.
